United States Patent Office

Des. 182,466
Patented Apr. 8, 1958

182,466

LOCK FOR LUGGAGE CASES AND THE LIKE

Erwin Kalla, West Pittsburg, Pa., assignor to Reliable Luggage, Inc., West Pittsburg, Pa., a corporation of Pennsylvania

Application June 5, 1957, Serial No. 46,488

Term of patent 14 years

(Cl. D50—7)

Fig. 1.

Fig. 2.

Fig. 1 is a front elevation of a lock for luggage cases and the like, showing my new design; and

Fig. 2 is a right end view of Fig. 1.

I claim:

The ornamental design for a lock for luggage cases and the like, as shown.
